UNITED STATES PATENT OFFICE.

WINCENTY KRAGIEL, OF NORWALK, CONNECTICUT.

LOCK.

1,280,764.

Specification of Letters Patent.

Patented Oct. 8, 1918.

Application filed August 10, 1915. Serial No. 44,827.

To all whom it may concern:

Be it known that I, WINCENTY KRAGIEL, a subject of the Czar of Russia, and resident of Norwalk, in the county of Fairfield and 5 State of Connecticut, have invented certain new and useful Improvements in Locks, of which the following is a specification.

This invention relates to locks and latches and particularly to automatically timed controlled locks associated with novel means for 10 opening the lock at a predetermined time.

An object of this invention is to provide a door with latches intended to hold the door in closed position, said latches being 15 automatically actuated to cause the said latches to interlock with the door jamb, safe structure or the like, mechanism being provided for actuating the said latches to unlock the same and novel means being provided whereby a clock or timing mechanism 20 communicates motion to the latch actuating mechanism for withdrawing the latches and unlocking the door. A further object of this invention is to provide novel means 25 for mounting the clock or timing mechanism with relation to the door and the operating parts of the latches.

With the foregoing and other objects in view, the invention consists in the details 30 of construction, and in the arrangement and combination of parts to be hereinafter more fully set forth and claimed.

In describing the invention in detail, reference will be had to the accompanying 35 drawings forming part of this specification wherein like characters denote corresponding parts in the several views, and in which—

Figure 1 illustrates a view in elevation 40 of a fragment of the interior of a door with the invention applied thereto;

Fig. 2 illustrates a view similar to Fig. 1 showing the latch actuating mechanism in position with the latches withdrawn;

45 Fig. 3 illustrates a view similar to Fig. 2 with the latch actuating mechanism released and the latches in locked position;

Fig. 4 illustrates an end view of a fragment of the locking mechanism;

50 Fig. 5 illustrates a sectional view on the line 5—5 of Fig. 1;

Fig. 6 illustrates a sectional view on the line 5—5 of Fig. 1, with the timing mechanism in a different position of adjustment 55 with relation to the lock actuating means;

Fig. 7 illustrates a perspective view of a

cam for moving the lock actuating mechanism;

Figs. 8 and 9 are perspective views of fragments of a shaft with the lugs thereon; 60 and

Figs. 10, 11 and 12 illustrate perspective views of fragments of the mechanism.

In these drawings 15 denotes a fragment of a door having guides 16 in which the 65 latches 17 are slideable. Each latch has a shank 18 and an extension 19 which is slideable in a bracket 20 and at the junction of the shank and extension, there is a flange 21 against which a latch operating arm 22 70 works for the purpose of retracting the latch against the action of a spring 23 which spring encircles the extension and is interposed between the bracket 20 and the flange 21. The function of the spring is to press 75 the latch normally outward and to hold it in locked position and the function of the arm 22 is to retract the said latch.

It is to be understood that a plurality of latches may be employed but the foregoing 80 description of the latch and its associated parts will suffice as a description of the additional latches and it is the purpose of the inventor to simultaneously actuate the latches to retract them through mechanism 85 which will now be explained.

A shaft 24 is journaled in the bearings 45 carried by the door and said shaft has a plurality of cam lugs 25 for a purpose to be presently explained. The upper portion of 90 the shaft 24 has a lug 26 engaged by a bolt 27 which is slideable in the guide 28 secured to the door and the bolt is held normally projected by a spring 29 which encircles the bolt 27 between a guide bracket 30 and a 95 shoulder 31 formed on the bolt. The inner end of the bolt has a shoulder 32 which is engaged by a lug 33 on a rock shaft 34 which is journaled in the door 15 the said rock shaft being operated by a pin 35 which 100 slides vertically in the guide and is adapted to bear against a lug 36 projecting from the rock shaft, the said lug 36 being at an angle with relation to the lug 33. When pressure is applied to the pin 35, its head bears 105 against the lug 36 and moves the rock shaft and the said lug 33 which is in engagement with the shoulder 32 of the bolt causes a movement of the bolt longitudinally of the guide, thus withdrawing the projecting end 110 of the said bolt from the lug on the shaft and releasing the said shaft, permitting the

latches of the door to be forced into locked position by the mechanism heretofore explained.

As a means for operating the shaft 24 at predetermined times, timing mechanism is employed, the said timing mechanism being here shown as a plurality of alarm clocks 37 each provided with an alarm winding stem 38^a. Each clock casing is secured to the housing 39 in which the shaft 24 is journaled by means of fastenings 40 such as screws and the winding stem 38^a of the clock is provided with a camming block 41 which engages the cam lug 25 on the said shaft. When the alarm mechanism is set for a certain hour and the alarm "goes off" the alarm winding stem is rotated by the clock mechanism, thus carrying the camming blocks 41 into engagement with the cam lugs 25 and causing the depression of the said camming lugs and the partial rotation of the shaft 24 which carries the said lugs. The partial rotation of the said shaft results in the partial oscillation of the arms 22 which, in turn, engage the flanges of the shanks of the latches and retract the said latches. As the shaft 24 partially turns, the bolt 27 slides under the lug 26 and the parts are held against further movement until the pin 35 is actuated and the bolt is withdrawn from under the lug. It is the purpose of the inventor to provide a pin engaging arm 42 on the structure with which the door coacts with which the end of the pin 35 comes in contact when the door is closed so that the pin will be pushed in to rock the shaft 34 and withdraw the bolt, releasing the shaft so that it may be swung under the action of the springs on the extensions of the shanks of the latches.

In order that access may be had to the back of the clock for the purpose of winding, setting or the like, the housing 39 is mounted on hinges 43 and the housing is held in the position shown in Figs. 5 and 6 by a spring clip 44 having an aperture to receive the pin 45 which projects from the face of the side plate of the housing. By reason of the fact that the housing is mounted to swing as stated, the clocks may be accessible so that the timing mechanism and the alarm mechanism may be wound.

As a means for arresting the alarm mechanism when the winding stem has rotated a predetermined distance, the said winding stem 38^a is provided with a projecting member 46 which comes into contact with a vibrator 47, which vibrator 47 is the ordinary bell hammer used in alarm clocks.

Fig. 5 illustrates the clock and mechanism in position prior to its being operated to unlock the door and Fig. 6 shows the parts in the position which they assume when the door is being unlocked.

I claim—

1. In a lock, guides carried by a door,

latches slideable in the guides, a shaft journaled in operative relation to the said latches, means for communicating motion of the said shaft to the latches for retracting the latches, cam lugs on the said shaft, timing mechanism, means driven by the timing mechanism for engaging the cam lugs for partially rotating the shaft, means for holding the shaft in position to which it is moved by the timing mechanism, and means for actuating the shaft retaining device for releasing said shaft when the door is closed. 70 75

2. In a lock, guides carried by a door, latches slideable in said guides, a shaft journaled in operative relation to the said latches, means whereby rotary motion of the shaft is communicated to the latches for withdrawing the same, means for projecting the said latches when released by the shaft actuating members, a timing mechanism including an alarm and an alarm winding stem, a cam carried by the said winding stem, cam engaged members on the shaft whereby the motion of the timing mechanism is communicated to the shaft for partially rotating the same, means for holding the shaft in the position to which it is moved by the timing mechanism, and means operated by the closing of the door for withdrawing the said retaining means. 80 85 90

3. In a lock, guides carried by a door, latches slideable in said guides, a shaft journaled in operative relation to the said latches, means whereby rotary motion of the shaft is communicated to the latches for withdrawing the same, means for projecting the said latches when released by the shaft actuating members, a timing mechanism including an alarm and an alarm winding stem, a cam carried by the said winding stem, cam lugs on the shaft engaged by the cam of the winding stem, means for holding the shaft in the position to which it is moved by the timing mechanism, and means operated by the closing of the door for withdrawing said retaining means. 100 105 110

4. In a lock, a housing carried by a door and hinged thereto, a timing mechanism secured in the housing, said timing mechanism including an alarm and its winding stem, a cam on the said winding stem, a shaft journaled on the door having means engaged by the cam for partially rotating the shaft, latches actuated by the said shaft, means for holding the shaft in the position to which it is moved by the timing mechanism, means for releasing the said shaft when the door is closed, and means for moving the latches in a direction opposite to that in which they were moved by the shaft whereby the latches are projected into locked positions. 115 120 125

5. In a lock, a hinged casing carried by a door, timing mechanisms secured to the casing and adapted to be carried by said casing so that access to the back of the timing mech- 130

when it is moved by the timing
mechanisms, and means for removing the
retaining means when the door is
closed.

In a lock, a hinged casing carried by a
timing mechanisms secured thereto so
access may be had to the back of the

In testimony whereof, I affix my signature 30
in the presence of two witnesses.
